RAILWAY JOURNAL BOX LUBRICATOR

James J. Hennessy, Chambersburg, Pa., assignor to Hennessy Lubricator Company, Inc., Chambersburg, Pa., a corporation of Delaware

Application September 10, 1952, Serial No. 308,831

11 Claims. (Cl. 308—84)

This invention relates to railway axle journal lubricators and comprises a novel pump and distributor adapted to be applied to the face of the journal and adapted to receive lubricant from a pump and deliver lubricant over a large area of the journal.

One object of the invention is to filter and screen the lubricant in its passage to the journal so that cinders, dust, sand or other fragments of a gritty, hard nature will not be fed into contact with the journal surface.

A further object of the invention is to avoid feeding to the journal fibers, lint and other particles of waste which may accumulate under the journal bearing as a result of "waste grab" which may produce undue heating of the journal and results in glazing.

A still further object is to provide a distributor with an inertia-operated lubricant pump which will supply an adequate amount of lubricant to a relatively wide area of the distributor before bringing it into contact with the journal.

Another object of the invention is to provide a lubricant pad construction for an oil reservoir compartment which maintains, independent of pump action, a quantity of oil in the distributor. Even if the oil in the pump and box has been congealed by cold weather, or if the pump is not effective for other reasons, the oil trapped in the distributor will lubricate the journal in its initial operation until the oil is heated by friction or until the pump is inspected.

Another object is to pump lubricant from the bottom of a journal box to the journal by inertia of a weight within the distributor.

These and other detailed objects are attained by the structure illustrated in the accompanying drawings, in which:

Figure 1 is a transverse vertical sectional view through the lower portion of a railway axle journal and box and the distributor.

Figure 2 is a longitudinal vertical section through the structure shown in Figure 1.

Figure 3 is a longitudinal section on the line 3—3 of Figure 2, showing the arrangements of the inlet valves.

The journal 1 mounts a box 2 in the usual manner. The lubricant pump is positioned between the lower wall of the box and the journal. It includes a pump body having a bellows-like side wall 3 of flexible plastic such as is marketed under the name "neoprene" or similar oil impervious material and includes a lower wall 4 of sheet metal. Wall 4 is provided with inlet openings 5 and a similar upper wall 6 is provided with outlet openings 7. Associated with openings 5 is a disc 14 with retainer 14a forming a flap valve. A coil spring 17 thrusts walls 4 and 6 apart.

The pump upper wall 6 has a flap disc 18 provided with openings 19 and forming an outlet valve. Attached to flap 18 is a weight 21 with a transverse passage 22.

A casing 8 is secured at its lower end to pump side wall 3 and is made of similar material and may lie against the wall of the journal box. It carries the distributor pad 9 of chenille, felt, waste yarn, or similar soft porous material permeable to oil under pressure and exerting a filtering action to trap dirt, lint, etc., in the oil as it passes upward through the pad. The pad includes a journal engaging cover 10 preferably knitted of hard twine woven to a thin porous back 11 which is sewn to the upper edge of casing 8. Inside the pad are springs 13 or some resilient material, such as sponge rubber, which prevent pad

2

9 from packing down and holds cover 10 against journal 1.

In operation, oil is supplied to the lower part of journal box 2 where it collects under the lower wall 4 of the pump. As the vehicle travels, it is subject to shocks, jolts, and jars which cause weight 21 to operate by inertia to compress spring 17 and the action and reaction of the weight and spring results in pumping the oil past and around inlet valve disc 14, filling the pump body 3 with oil and then discharging oil through outlet valve disc 18 to packing 9 which leads the oil by capillary action to cover 11 and the surface of the journal.

The hard twine of cover 10 will feed oil to the journal surface but will not fray and separate like cotton waste and gather between the journal and bearing.

The details of the structure may be varied substantially without departing from the spirit of the invention and the exclusive use of those modifications coming within the scope of the claims is contemplated.

What is claimed is:

1. In a railway journal lubricator including a lubricant distributor comprising a top cover for application to a journal, a mass of fibrous material beneath the cover, a casing enclosing the material and secured to the cover, a pump comprising a flexible body with top and bottom walls forming a portion of said casing, means yieldingly thrusting said walls to a predetermined normal position, and an operating weight within said casing and associated with one of the pump walls to move said walls relative to each other against the thrust of said means by the inertia of the weight.

2. A railway journal lubricator as described in claim 1 in which the distributor is mounted on springs which support the lubricator independently of the pump.

3. A lubricator as described in claim 1 in which coil springs are compressed between the pad and opposite portions of the casing and provide supports for the lubricator independently of the pump.

4. A lubricator as described in claim 1 in which the lowermost wall of the pump and casing is formed by a substantially rigid plate and the yielding means associated with the pump walls comprises a spring seated on said plate, and the operating weight is carried on said spring.

45 5. In combination with a lubricant distributor comprising a pad with an outer surface arranged for application to the surface of a journal to be lubricated, an oil reservoir having a flexible wall depending from the perimeter of said pad, an oil filter contained in said reservoir, and underlying said pad, a pump provided with an inlet valve and with an outlet valve discharging to said reservoir, and a weight associated with said flexible wall to operate said pump by its inertia.

55 6. A railway journal lubricant distributor comprising a relatively thick and stiff pad of fibrous material for application to a journal to be lubricated, a relatively thin and flexible sheet of oil-impervious material secured marginally to the pad and forming a compartment beneath the pad, a mass of loosely assembled fibers forming a filter disposed between said sheet and the pad, and pump structure forming a valved passage through said sheet for delivery of lubricant to said fibers.

65 7. A railway journal lubricant distributor comprising a container including a cover of relatively hard knitted material for application to the surface of a journal and a casing of oil-impervious material secured to the marginal portions of said cover, yielding means between said cover and casing for holding the container expanded, and lubricant pump structure at least partly received in said container and provided with a passageway for lubricant from below the casing to the interior of the container.

8. A railway journal lubricant distributor comprising a relatively thick and stiff pad of fibrous material with a substantially imperforate face from side to side and from end to end of the pad for application to a journal to be lubricated, a relatively thin and flexible sheet of oil-impervious material secured marginally to the pad and forming a compartment beneath the pad, there being a passage through said sheet for delivery of lubricant to the underside of the pad, and a mass of loosely assembled

fibers forming a filter disposed between said sheet and the pad.

9. A railway journal lubricator comprising a lubricant distributor including a container having a journal-engaging upper cover of oil-permeable material and a lower casing of flexible oil-impervious material depending from the perimeter of said cover, there being a mass of fibrous material substantially filling said container, yielding means thrusting said cover and the lower portion of said casing apart and forming a support for said cover, and a pump enclosed by the container including an inertia weight and a yielding support for the same independent of said means.

10. A railway journal lubricator distributor comprising a lubricant container having an upper cover of knitted hard twine with a concave arcuate contour for application to a journal, and a casing of flexible impervious material depending from the perimeter of said cover, there being a mass of fibrous material substantially filling said container, and supporting springs spaced apart transverse- 20

ly of the axis of the arcuate contour and diverging downwardly, the lowermost portion of said casing being arched upwardly between the lower portions of said springs to form a recess of substantial volume at the lower center of the distributor.

5 11. A railway journal lubricator comprising a distributor as described in claim 10 and a pump including an inertia weight within the lubricant container and a spring support for the weight positioned in said recess and in 10 the area between the container-supporting springs.
